United States Patent

Des. 235,303
Patented June 10, 1975

235,303

PATTY PRESS

Richard A. Boucher, 263 Davis St.,
Northboro, Mass. 01581

Filed Aug. 16, 1973, Ser. No. 388,873

Term of patent 14 years

Int. Cl. D7—04

U.S. Cl. D7—43

FIG. 1.

FIG. 2.

FIG. 3.

FIG. 4.

FIG. 1 is a top plan view of a patty press showing my new design;

FIG. 2 is a side elevational view thereof;

FIG. 3 is a bottom plan view thereof; and

FIG. 4 is a cross-sectional view thereof taken along line 4—4 of FIG. 2.

I claim:

The ornamental design for a patty press, substantially as shown.
